UNITED STATES PATENT OFFICE.

WILLIAM R. DERR AND SAMUEL SMITH, OF NEW YORK, N. Y.

CLOTHES-LINE AND LOCKING-PIN THEREFOR.

1,265,436.

Specification of Letters Patent.

Patented May 7, 1918.

Application filed August 21, 1917. Serial No. 187,491.

To all whom it may concern:

Be it known that we, WILLIAM R. DERR and SAMUEL SMITH, both citizens of the United States, and both residents of New York, county and State of New York, have jointly made and invented certain new and useful Improvements in Clothes-Lines and Locking Clothes-Pins Therefor, of which the following is a specification.

Our invention relates to clothes-line apparatus, and has for its object to provide means for attaching garments or clothes to a clothes-line and so securing them thereto as to prevent their theft, or from being accidentally detached or blown away.

A serious cause of complaint from the occupants of apartment houses is that garments and clothes are continually maliciously stolen from the clothes-lines which are provided upon the roof for the use of the tenants. Indeed, in some instances, this has become sufficiently serious to cause the superintendent to provide wire cages upon the roofs of apartment houses including means for drying the clothes in said wire cages or inclosures. It is therefore among the objects of our invention to provide a simple and comparatively inexpensive apparatus which will prevent the malicious stealing of the clothes, this object being obtained by the use of locking clothes-pins. The foregoing objects are accomplished in a simple and expeditious manner, the apparatus being so designed that it may be conveniently used and operated, allowing the clothes or garments to be attached and locked upon the clothes-line in a ready manner, and also conveniently unlocked and detached from the line by a properly authorized person.

With the foregoing and other objects in view, our invention resides in the combination and arrangement of parts and in the details of construction hereinafter described and claimed, it being understood that changes in the precise embodiment of the invention may be made within the scope of what is claimed without departing from the spirit thereof.

The preferred embodiment of our invention is disclosed in the accompanying drawings, wherein:

Figure 1 is a view in perspective of an apparatus embodying the characteristic features of our invention, illustrating several garments securely locked in position upon a clothes-line;

Fig. 2 is an enlarged view of one of the locking clothes-pins, showing its method of support and the manner in which it locks clothes or garments to the clothes-line; 60

Fig. 3 is a view in top plan view thereof;

Fig. 4 is a view in section taken on the line 4—4 of Fig. 2, the jaws of the clothes-pin being open prior to insertion of the clothes therein; 65

Fig. 5 is a similar view showing the jaws of the clothes-pin locked in closed position, rigidly holding the garment to the clothes-line;

Fig. 6 is a view in horizontal section taken on the line 6—6 of Fig. 2;

Fig. 7 is a fragmental view illustrating the manner in which the wedging members of the clothes-pin are withdrawn when it is desired to remove the clothes from the line. 75

Referring specifically to the several views, each clothes-pin is formed of the two jaws 10, having inwardly projecting side walls 11, which are hinged together by the pin 12. A coil spring 13 extends around the pin 12 80 and resiliently holds the lower clamping extremities of the jaws in closed position, as illustrated in Fig. 5. The upper extremities of the side walls of the jaws which project one within the other, as more clearly shown 85 in Fig. 6, are provided with the recesses 14 which define aligned openings 15 in which is slidably mounted a wedge-shape locking member 16. The wedge-shape locking member, being located remote from the clamping extremities 17 of the clothes-pin, is adapted to force the clamping extremities together and rigidly lock them in such position. The clothes-pins are held in proper relation to the clothes-line and at the desired 95 distance apart, (so that the clothes-pins will be simultaneously locked and unlocked by the wedge members) by the supporting member 19 which preferably is formed of a wide flat band with rounded edges, so that 100 the clothes will not be torn should they be blown thereagainst. The supporting member 19 extends between the two posts 20 and is spaced a slight distance above the clothes-line 21, which is also attached to the said 105 posts. The wedge members 16 are preferably secured upon a continuous wire or support 22, the clothes-pins, clothes-line, and other parts, being formed of such substance as galvanized iron, so that the clothes are protected 110 from rust stains. A lever 23, connected to one of the posts or supports 20, is attached

to the connecting wire or member 22 of the wedge members, and is provided with a lock 24 whereby all of the wedge members may be locked in their operative positions.

5 The apparatus as thus described contains many desirable features, among which attention is called to the ease with which the clothes-pins may be operated and the facility with which garments may be positioned 10 over the clothes-line and clamped and locked thereto. The spring 13 which tends to force the jaws of the clothes-pin against the clothes-line, may be omitted if desired, but when included, facilitates the attachment of 15 clothes to the clothes-line. The inwardly projecting side walls 11 of the jaws of the clothes-pins extend one beyond the other, so as to prevent an instrument being inserted between the jaws and prying them open. A 20 wedge member, remote from the locking lever 23, is connected by a wire or flexible element 25 to the post or support 20, and is of sufficient length to allow the wedge members to be forced into their operative positions, holding the jaws of the clothes-line 25 closed. When the lever 23 is released, a slight pull upon the connecting member 25 will instantly retract all of the wedge members and allow any or all of the clothes-pins 30 to be opened and the garments released from the lines. If it is so desired, the connecting member 25 may be formed of resilient material and so automatically effect the retraction of the wedge members when the lever 23 is released. As shown in the drawings, the connecting member 25 may be secured to a weighted lever 26, so that, as more 35 clearly illustrated in Fig. 7, when the locking lever 23 is released, the weight of the supplemental lever 26 will automatically effect the withdrawal of the wedge members 40 and accordingly release the jaws of the clothes-pins.

What we claim is:

45 1. An apparatus of the class described comprising a clothes-line, a plurality of clothes-pins mounted in proximity thereto, and means whereby said clothes-pins are forced into contact with the clothes-line and 50 the contents thereof and locked in such position.

2. An apparatus of the class described

comprising a clothes-line, a plurality of clothes-pins each formed with hinged jaws mounted adjacent said line, wedge members 55 engaging said clothes-pins and adapted to force the clamping extremities thereof together and hold them in such position, and means for locking said wedge members in 60 operative position.

3. An apparatus of the class described comprising a clothes-line, a plurality of clothes-pins supported so that the clamping extremities thereof are adapted to engage said clothes-line, wedge members engaging 65 said clothes-pins and adapted to force the clamping extremities thereof around said clothes-line and bind and hold garments and similar articles upon said line, and a lock operating in conjunction with said wedge 70 members and preventing their retraction.

4. An apparatus of the class described comprising a clothes-line, a plurality of clothes-pins supported adjacent said clothes-line, with the clamping extremities of said 75 clothes-pins adapted to fasten clothes or similar articles in position upon said clothes-line, means engaging said clothes-pins adapted to hold the clamping extremities thereof in closed position around said line, 80 an operating connecting member engaging said means, adapted to operate the same, and a lock holding said connecting member against movement.

5. An apparatus of the class described 85 consisting of a clothes-line, a plurality of clothes-pins supported in proximity to said line and engaging the same, said clothes-pins consisting of hinged jaws, members engaging said jaws preventing the opening of 90 the same, a connecting member extending between said holding members and adapted to move the same into and out of operative position, holding the jaws in closed position, or allowing them to open, respectively, and 95 a lock associated with said connecting member, holding the same against movement.

Signed at New York, county and State of New York, this 13th day of August, 1917.

WILLIAM R. DERR.
SAMUEL SMITH.
